UNITED STATES PATENT OFFICE.

WHITMAN G. JONES, OF GREAT FALLS, MONTANA.

WIRE-HOIST.

1,233,244.

Specification of Letters Patent.

Patented July 10, 1917.

Application filed May 5, 1916, Serial No. 95,722. Renewed February 7, 1917. Serial No. 147,255.

To all whom it may concern:

Be it known that I, WHITMAN G. JONES, a citizen of the United States, residing at Great Falls, in the county of Cascade, State of Montana, have invented certain new and useful Improvements in Wire-Hoists; and I do hereby declare the following to be a full, clear, and exact description of the invention, such as will enable others skilled 10 in the art to which it appertains to make and use the same.

This invention relates to a wire hoist.

An object of the invention resides in the provision of a device by means of which a plurality of wires, which are normally supported on the cross arm of a telegraph pole, may be lifted so as to permit a house to be moved beneath the same.

A further object of the invention resides 20 in the provision of a device of this character which may be readily set in place and easily operated.

With these and other objects in view, such as will appear as my description progresses, 25 my invention comprises the combination and arrangement of parts as set forth in and falling within the scope of the appended claims.

In the drawing:

30 Figure 1 is a side elevation of a device constructed in accordance with my invention showing the same applied to a telegraph pole with the wires lifted;

Fig. 2 is a front elevation of the same 35 with the parts in the positions shown in Fig. 1 of the drawing;

Fig. 3 is a transverse sectional view showing the construction of the upper guides;

40 Fig. 4 is a similar view showing the construction of the lower guides;

Fig. 5 is an elevational view of the device when the parts are in their folded positions, and

45 Fig. 6 is a section on line 6-6 of Fig. 1.

In the drawing I have illustrated a telegraph pole 1 which is provided with the usual supporting cross arm 2.

In order that the wires may be lifted from 50 this cross arm without necessitating their being cut, I have provided a standard 3 which is adapted to be secured to the pole in spaced relation thereto by means of a plurality of flexible tie members 4, the standard 55 being held in spaced relation by brackets 5 which are provided with arcuate portions or

seats 6 to bear against the pole 1. Slidably mounted on the standard 3 is a second standard 7 which is provided with a groove 8 into which a bead 9 on the standard 3 extends. 60 This bead and groove extend longitudinally of the standards 3 and 7 so that the standard 7 may be moved relatively to the standard 3 but will be guided thereon. A pair of guides is mounted adjacent the upper end 65 of the standard 3, which guides include strips 10 which extend outwardly from and are secured to the standard 3. An antifriction roller 11 extends between the ends of the strips 10 and bears against the outer face 70 of the movable standard 7. A pair of guides are secured adjacent the lower end of the standard 3 and these guides are different in form than the guides adjacent the upper end and include a strip which is bent to 75 form arms 12 and to embrace the rear of the standard 3. The forward ends of these arms 12 are bent inwardly as at 13 to retain the movable standard 7 in place. A space 14 is however provided between the 80 ends of the strips 12 for a purpose which will later appear.

In order that the standard 7, which carries at its upper end a cross arm 15 for the reception of the wires 16 which are 85 normally supported by the cross arm 2 of the pole 1, may be raised and lowered, I have secured a bracket 17 to the standard 3 adjacent its upper end, on which bracket a pulley 18 is mounted and have 90 provided a pulley 19 adjacent the lower end of the standard 7. A flexible operating member 20 passes about these pulleys 18 and 19 and thence to a position within convenient reach of the operator. The 95 lower end of the standard 3 is provided with a seat 21 into which a tongue 22 on the lower end of the movable standard 7 projects when the latter is folded upon the former.

In operating the device it is secured to the pole 1 by means of the flexible members 4 with the brackets 5 engaging the pole. The wires 16 are detached from the cross arm 2 of the pole and the member 20 operated to move the standard 7 upwardly. When the cross arm 15 on this standard engages the wires and the standard is moved upwardly farther, the wires will be raised from the cross arm 2 110 to the desired height so that a house may be moved beneath the wires. When the

wires are in their proper positions, that is to say, in their proper raised positions, the flexible member 20 may be suitably secured and the wires will be maintained 5 in their raised positions.

While I have illustrated and described a particular embodiment of my invention, it has merely been for the sake of convenience and I do not wish to be limited 10 to that particular embodiment as it is obvious that numerous changes may be made in the details of construction without departing from the spirit of the invention or exceeding the scope of the appended 15 claims.

What I claim is:—

1. In a device of the class described, the combination with a standard having brackets extending outwardly therefrom, which 20 brackets are provided with arcuate seats, of a standard slidably mounted on the first mentioned standard, means adjacent the upper end of the first mentioned standard for guiding the last mentioned standard in its movement, which means consists of a pair of 25 strips and a roller extending between the ends of the strips and engaging the outer face of the second mentioned standard,

guides adjacent the lower end of the first mentioned standard including a pair of strips having ends turned inwardly toward each other and engaging the outer face of the second mentioned standard and terminating in spaced relation to each other and means for elevating the second mentioned 35 standard.

2. In a device of the class described, the combination with a standard having pole engaging brackets thereon, means for securing said brackets to a pole, a second standard slidably mounted on and longitudinally of the first mentioned standard and having a cross bar at its upper end, guides secured to the first mentioned standard and embracing the second mentioned standard, a seat formed at the lower end of the first mentioned standard and a complementary tongue formed on the lower end of the second mentioned standard.

In testimony whereof, I affix my signature, in the presence of two witnesses.

WHITMAN G. JONES.
